United States Patent Office

Des. 228,822
Patented Oct. 23, 1973

228,822

INVALID WALKER

Francis A. Vesey, P.O. Box 516, Lakeside, Ariz. 85929
Filed Sept. 7, 1972, Ser. No. 287,273

Term of patent 14 years

Int. Cl. D24—99
U.S. Cl. D88—5 R

FIG. 1 is a front perspective view of an invalid walker showing my new design;

FIG. 2 is a rear perspective view thereof;

FIG. 3 is a side perspective view thereof in a folded position.

I claim:

The ornamental design for an invalid walker, as shown and described.
